CALVIN N. WENRICH, OF LANCASTER, PENNSYLVANIA, ASSIGNOR TO ARMSTRONG CORK COMPANY, OF PITTSBURGH, PENNSYLVANIA, A CORPORATION OF PENNSYLVANIA.

LAYING LINOLEUM OR THE LIKE.

Application filed January 15, 1927. Serial No. 161,421.

The present invention relates to laying linoleum or similar floor coverings, and more especially to the laying of linoleum with a reinforced felt between it and the floor.

5 It has been found that when linoleum is cemented directly to a wood floor, the linoleum is frequently torn due by the contraction of the boards causing the joints between the floor boards to open. Also, the inequalities in the floor boards are visible through the laid linoleum.

It is therefore customary in laying linoleum to cement a layer of heavy builder's felt to the floor and to cement the linoleum on top 15 of the felt. By this method the felt takes the strain of the contracting floor boards, leaving the linoleum intact. The felt also makes a resilient backing for the linoleum and prevents the outlines of the floor boards from becoming visible through the linoleum. It has been found, however, that there is a tendency 20 for the felt to split along splitting or cleavage planes parallel to the sheet of felt. The upper layers of felt which are cemented to the linoleum get pulled away from the lower layers of the sheet of felt which are cemented to the floor. This is particularly noticeable along the joints between the pieces of linoleum. The linoleum along the joints at times 25

30 has a tendency to curl upwardly. This tendency of the edges of the linoleum to lift or curl upwardly is, of course, resisted by the felt. The felt, however, is sometimes split by the upward lift of the linoleum so that 35 the edges along the seam are noticeably raised. The felt itself is made in layers which can be pulled apart so that the felt has little resistance to splitting between its component layers, and therefore does not have the structural strength to hold the linoleum tightly in 40 place against the floor. This liability of the felt to split is sometimes manifest in the middle of a piece of linoleum. For some reason there may be a buckling tendency in the

45 linoleum and this will cause the linoleum to rise into a sort of "blister". An examination of such blistered places shows that the bottom of the felt is usually firmly cemented to the floor and the upper face of the felt 50 firmly cemented to the linoleum, but that the body of the felt has pulled apart in a horizontal plane of separation.

The relative lateral movement between the

floor and the linoleum due to contraction or expansion of the floor boards has a tendency 55 to move the upper face of the felt laterally with respect to its lower face, and to rupture the horizontal cleavage planes between the laminae of the felt.

These defects are overcome in accordance 60 with my invention by reinforcing the felt so as to give it structural strength and prevent it from being pulled apart. This is preferably done by stitching the felt, although it may be done otherwise, as by adhesives.

65 In the drawings, which illustrate the preferred embodiment of my invention,—

Figure 1 is a perspective view of a floor upon which linoleum is being laid with reinforced felt;

Figure 2 is a sectional view through the floor linoleum and felt; and

Figure 3 is a detail view showing a modified form of stitching.

70 Referring to the illustrated embodiment of the invention, reference numeral 1 indicates a wooden floor made up of floor boards 2. In laying the linoleum a layer of builder's felt 3 is cemented directly upon the floor boards with the usual cement. The linoleum 4 is 75 then cemented directly over the felt with the usual linoleum cement.

75 As shown in the drawings, the felt is reinforced by lines of stitches 5 which are sewed along the strips of felt. The lines of the 80 stitches are preferably about three-quarters of an inch apart and are sewed with a medium sized thread. For convenience of manufacture, the lines of stitches are usually run lengthwise of the felt so that it may be 85 stretched as it is manufactured. The lines of stitches should be sufficiently close together to overcome the tendency of the felt to split apart in layers when it is subjected to the lifting action of the linoleum which is cemented 90 to its upper face.

95 While it is preferred, because of cheapness of manufacture, to have the stitches in parallel lines running lengthwise of the piece of felt, the felt can also be stitched crosswise 100 or quilted, as shown in Figure 3.

105 While I have found the stitching with cotton thread to be satisfactory, the stitching might be otherwise carried out, as by wire stitches or staples.

It is preferred to reinforce the felt by

- thread or staples which do not impair the yielding qualities of the felt or interfere with the adhesion of the usual cements. However, the felt might be otherwise reinforced so as to give it the requisite structural strength against splitting, as by impregnating it with a strengthening adhesive, such as glue, asphalt, etc., which will make the felt firmer but not stiffen it too much to prevent it from being pliable, and yielding enough not to be torn by expansion of the floor boards.

The strips of felt may be laid either across or with the direction of the floor boards. Also, the strips of linoleum may be laid either crosswise or in the same direction as the strips of felt. It is apparently immaterial whether the lines of stitching along the felt are parallel or run across the joints between the floor boards, or are parallel or run across the joints between the strips of linoleum. The troublesome splitting of the felt has not been splitting in cracks which extend vertically through the felt, but has been along horizontal cleavage planes between the naturally occurring laminations of the felt. This splitting can apparently be prevented by parallel lines of stitching provided the lines are sufficiently close together to prevent the upper part of the felt from being pulled away from the lower part of the felt.

While the reinforced felt is usually employed only in laying linoleums, it may be employed in the laying of other hard surfaced floor coverings, such, for example, as felt base goods.

The present invention is not limited to its illustrated embodiment, but may be otherwise embodied within the scope of the following claims.

I claim:

1. A floor covering comprising reinforced felt cemented to the floor and linoleum or similar hard surfaced floor covering cemented to the felt.
2. A floor covering comprising felt reinforced by lines of stitching cemented to the floor, and a linoleum or similar hard surfaced floor covering cemented to the felt.
3. The combination of a wooden floor, a lining cemented to the floor comprising felt reinforced by lines of stitching, and a linoleum or similar hard surfaced floor covering cemented to the felt.
4. The combination of a wooden floor, a linoleum or similar hard surfaced floor covering, and a lining between the floor and said floor covering comprising felt reinforced by lines of stitching.

In testimony whereof I have hereunto set my hand.

C. N. WENRICH.
